UNITED STATES PATENT OFFICE

2,484,704

PICKUP ASSEMBLY

Edward P. Girodat, Gull Lake, Saskatchewan, Canada, assignor of fifty per cent to Phillip Hyman, Gull Lake, Saskatchewan, Canada.

Application February 10, 1947; Serial No. 727,474
In Canada March 31, 1944

1. Claim. (Cl. 56—312).

1.

My invention relates to an improved pick-up assembly for attachment to the cutter-bar guards associated with harvesting implements such as combines, binders and the like; an object of the invention being to provide a device which will pick up all loose grain without the end thereof running into the ground.

A further object of my invention is to provide a device of the character herewithin described which is of eminently simple construction, economical to manufacture and which will give long service for the reason that breakages will be most infrequent since the device does not tend to run into the ground as does the conventional pick-up assembly.

With the above more important objects in view and such other minor objects as may appear as the specification proceeds, my invention consists essentially in the arrangement and construction of parts all as hereinafter more particularly described; reference being had to the accompanying drawings in which—

Figure 1 is a side elevation of a pick-up assembly embodying my novel modifications thereto.

Figure 2 is an exploded perspective view of the parts 5 and 8 intended to illustrate the interior structure thereof.

My pick-up assembly comprises the conventional forwardly projecting bracket 1 which is bolted or strapped to the underside of the usual cutter-bar guards 2 at the points 3 and 4.

The forward end of the bracket 1 terminates in the stationary part 5 of the conventional two-part hub 6.

My pick-up element 7 comprises collectively the rotatable portion 8 of the hub 6 which is bolted to the portion 5 at the centre thereof by means of a conventional square headed bolt 9; the forwardly and downwardly curving runner 10 which projects forwardly from the rotatable portion 8; the upwardly and rearwardly diverging carrying arm 11 which joins the runner at the forward end 12 thereof; and the carrying arm itself.

The portions 5 and 8 of the hub 6 are hollow on the inside thereby providing a semi-circular housing portion 13 for a cushioning spring 14. This cushioning spring is positioned between the abutments 15 and 16, the former of which is integral with the stationary part 5 of the hub while the latter is integral with the rotating part 8. From the foregoing it will clearly be recognized that upon rotation of the pick-up element in a counterclockwise direction, as for in-

2.

stance when a rock or hillock is encountered, the upper end of the spring will ultimately come into contact with the abutment 15 to provide a cushioning effect. In this context it is however to be noted that the spring 14 is not intended to extend for the full length of the semi-circular housing portion 13, but functions, as already stated, only as a cushion or buffer. From this it will be understood that the element 7 is free to "pick-up" freely to a certain extent without the intervention of any resistance by the spring.

Upon the left hand side of the hub portion 8, with respect to Figure 1, is a semi-circular slot 17 through which a nut and stop-bolt assembly 18 projects; it being understood that the nut of the assembly 18 may be bolted at any point upon the length of the slot 17, being intended to come up against the abutment 19 and which projects from and is integral with the hub portion 5.

20 In this way, the position of the pick-up element 7 may be adjusted, although it is to be understood that in the adaptation of the foregoing structure to my purpose I do not make use of such adjustment, and furthermore, make 25 use of a shorter and weaker spring than is commonly used in association with pick-up attachments. As has been clearly indicated in the accompanying Figure 1, I permit the runner and carrying arm 10 and 11 to drop clockwise so that the forward end 12 thereof is as low as possible. Thus it will occupy a position in a plane which is wholly below the lowermost peripheral limit of the hub, or in other words, as low as is permitted by the stop 20 which projects inwardly from the rotating part 8 and moves in the recess 21 in the stationary part 5 until it comes up against either of the shoulders 22 at the ends thereof.

40 All the foregoing represents conventional structure in relation to pick-up assemblies for attachment to cutter-bar guards with the exception of the fact that my spring 14 is shorter than those commonly used, which latter occupy, while in varying degrees of tension, the full 45 length of the housing portion 13. In conventional practice however it is to be understood that it is only very rarely that it is at all practicable to permit such an adjustment of the hub 6 that the forward end 12 may drop down as far as is permitted, because under such circumstances the point or end 12 repeatedly digs into the ground causing frequent stoppage, breakages and sometimes serious damage.

It is however desirable for maximum down-grain recovery that the pick-up element 7 be

inclined downwardly to the maximum extent illustrated so as to prevent its digging into the ground. I therefore provide the novel structure in advance of the junction or point 12, which consists of the forwardly projecting and upwardly curved extension finger 23, which is preferably formed of steel and thus is easily bent to the curvature desired, this member being welded to the point 12 as clearly illustrated. By the use of this forwardly projecting and upwardly curved extension finger I have found that it is perfectly practicable under most harvesting conditions to slacken the nut and bolt assembly 18 such that the pick-up element as-a-whole may drop to its limit as illustrated.

Only when the forward end of the pick-up element is in its lowermost position is it possible to pick-up the maximum amount of loose grain, but without the extension finger 23, this is not practicable for which reason the forward end 12 must be raised by adjustment of the nut and bolt assembly 18 in the slot 17. But obviously this permits the escape from underneath the pick-up element of a considerable quantity of loose grain. However, by the use of the extension finger 23 which I have now described, the maximum amount of loose grain is collected while avoiding the tendency of the element to dig into the ground.

Since various modifications can be made in my invention as hereinabove described and many apparently widely different embodiments of same made within the scope of the claims without departing from such spirit and scope, it is intended that all matter contained in the accompanying specification shall be interpreted as illustrative only and not in a limiting sense and I desire only such limitations placed thereon as are specifically expressed in the accompanying claim.

What I claim as my invention is:

A pick-up assembly for attachment to cutting-bar guards, comprising in combination a forwardly projecting bracket secured to said guard, a circular two-part hub, one part of which is

stationary and integral with one end of said bracket, a pick-up element, the other end of said hub being rotatable and integral with said pick-up element, means for holding said two-part hub rotatably together, a runner curving forwardly and downwardly from said hub, said runner constituting part of said pick-up element and being integral with and projecting forwardly from the rotatable part of said hub, a carrying arm diverging rearwardly and upwardly from the forward end of said runner, an upwardly curved deformable extension finger projecting forward from the junction of said runner and said carrying arm, a semicircular housing portion between the two parts of said hub, opposing abutments terminating said housing, one of said abutments being integral with the stationary part of said hub and the other integral with the rotatable part, a cushioning spring within said housing of a length less than that of said housing, the rotatable part of said hub being freely movable without resistance thereagainst by said spring when said runner attached thereto is in ground contacting position, the junction of said runner and said carrying arm lying in a plane below the lowermost peripheral limit of said hub when in situ and when the associated cutter-bar is lying in or below a horizontal plane.

EDWARD P. GIRODAT.
